[57] CLAIM

The ornamental design for a subsurface outrigger for the detection of magnetic fields, as shown and described.

DESCRIPTION

FIG. 1 is an isometric view of the invention;
FIG. 2 is a view in isometric form partially broken away;

FIG. 3 is a side view of the system of FIGS. 1 and 2;
FIG. 4 is a front view of the system of FIGS. 1 and 2; and

FIG. 5 is a rear view of the system of FIGS. 1 and 2.
The dotted lines shown in FIGS. 1-3, are disclosed for illustrative purposes only.

FIG. 4

FIG. 5
